(57) **CLAIM**

The ornamental design for racing bicycle handlebars, as shown and described.

DESCRIPTION

FIG. 1 is a front elevational view of the racing bicycle handlebars in accordance with the present invention; FIG. 2 is a front perspective view thereof; FIG. 3 is a left side elevational view thereof, the right side being a mirror image thereof; and, FIG. 4 is a top plan view thereof, the bottom being unadorned. The broken lines showing portions of the racing bicycle handlebars form no part of claimed design.
